UNITED STATES PATENT OFFICE.

ROBERT L. BENSON, OF CHICAGO, ILLINOIS.

PUMP.

SPECIFICATION forming part of Letters Patent No. 740,386, dated October 6, 1903.

Application filed August 22, 1900. Serial No. 27,704. (No model.)

To all whom it may concern:

Be it known that I, ROBERT L. BENSON, a citizen of the United States, residing at Chicago, in the county of Cook and State of Illinois, have invented a certain new and useful Improvement in Pumps, (Case No. 2,) of which the following is a full, clear, concise, and exact description, reference being had to the accompanying drawings, forming a part of this specification.

My invention relates to pumps, and more particularly to that class of pumps in which hollow piston-rods are employed for conveying the pumped fluid from the pump-barrel.

My invention comprises an improved form of valve that is very simple in construction and effective in operation and an improved arrangement of valves in the hollow piston-rod, whereby the construction of the pump is greatly simplified and the effectiveness of its operation increased.

In practicing the first feature of my invention I preferably employ a valve-stem that carries a valve at one end and is provided with a suitable enlargement at the other end that serves to prevent a removal of the valve-stem, which is loosely fitted within the valve-passage. The valve-stem is preferably formed of wire, and the enlargement carried thereby is preferably formed by a continuation of the wire that is bent into an eye.

The second feature of my invention, generally speaking, comprises a hollow piston-rod adapted to reciprocate within a suitable pump-barrel, a piston carried by the piston-rod and snugly fitting the pump-barrel, and a valve located directly in the hollow piston-rod upon each side of the piston, the valve-passages affording direct communication between the hollow bore of the piston-rod and the space within the pump-barrel.

Heretofore complicated valving means have been employed in pumps of this general type which required a great deal of space, were difficult of construction and repair, and incapable in many instances to effect their purpose.

I will explain my invention more fully by reference to the accompanying drawings, in which—

Figure 1 is a longitudinal sectional view of a pump constructed in accordance with my

invention; and Fig. 2 an enlarged longitudinal sectional view, an intermediate portion of the pump structure being broken away. 55

Like parts are indicated by similar characters of reference in the views.

The pump-barrel *a* is constructed of any suitable metal and is provided at its upper end with a closing-cap *b*, the outer rim of 60 which engages a gasket *c*, that may be of rubber, that is supported upon a rim *d*, integral with the pump-barrel *a*. The cylindrical rim of the cap *b* has threaded engagement at the upper end of the pump-barrel, by which 65 engagement the said rim is forced into firm contact with the gasket. The cap *b* is provided with a cylindrical elongation that constitutes a part of the stuffing-box *e*, through which the hollow piston-rod *f* is adapted to 70 reciprocate. The piston-rod *f* is preferably provided with an enlargement *g*, that serves to limit its downward travel, a transverse extension *h* of this enlargement being hollow 75 and braced thereby and having direct communication with the interior of the piston-rod and serving as a means of attachment for a duct *i*, that is preferably flexible and in the form of a rubber hose. A handle *k*, that may be grasped by an operator, is mounted upon 80 the upper end of the hollow piston-rod, the screw by which the handle is secured to the piston-rod serving to close the upper end of the said rod. The lower end of the piston-rod is provided with a closure-cap *l*, that preferably has threaded engagement therewith. 85

A piston *m* is provided near the lower end of the piston-rod and is secured thereto by means of washers *n n*, that have threaded engagement with the piston-rod. A valve *o* is 90 provided above the piston, and a valve *p* is provided below the same, these valves opening and closing the valve-passages provided in the piston-rod, which are adapted when the valves are in suitable position to afford direct communication between the interior of the piston-rod and the pump-barrel. I have found that where the valves *o* and *p* are entirely disengaged they may not operate perfectly under all circumstances, as owing to 95 the high degree of curvature of the piston-rod they are likely to be thrown out of adjustment with respect thereto and are not always likely to perfectly close the valve-pas-

sages. I therefore mechanically unite the valves by an interposed mechanical connection that serves to maintain the valves in proper alignment with respect to each other and with respect to the inner wall of the piston-rod, this interposed mechanical connection preferably being an integral part of a loose strip of leather, the ends of which constitute the valves proper. Valves *q* and *r* are provided at the upper and lower ends of the pump-barrel and operate in a manner to be hereinafter set forth, the valve *r* being contained within a screw-caps, inserted within a passage provided in the base of the pump, the passage having communication with the pump-barrel, as the drawings show. Each of the valves preferably comprises a wire stem *t*, which is bent into the form of an eye *u* upon the exterior of the pump-barrel and piston-rod, as indicated, the remaining ends of the valve-stems carrying the valves. In order that the valve structure *o* may not be injured by the upward movement of the piston-rod, I provide a collar *v* or other suitable form of stop, which by engaging the cap *b* serves to limit the upward travel of the piston-rod and to prevent the valve structure from coming in contact with the said cap. The stop *v* preferably contains a recess *w*, surrounding the piston-rod, the stop thus acting as a guard to collect oil that might otherwise flow down the piston-rod and minute particles of metal or other foreign substances that would otherwise be blown into the piston-rod and from the piston-rod blown through the duct *i*. I find it important to provide this shield, especially where the pump is used for atomizing or vaporizing apparatus used in the treatment of affections of the respiratory tract, as otherwise the foreign particles might find access to the system of the patient. I am thus enabled to provide a very simple and efficient pump structure whose parts are readily accessible, easily replaced and repaired.

The pump as herein described operates as follows: Assuming the piston to be traveling upwardly, the valve *r* will be opened, while the valve *p* will be closed, so that as the piston ascends fluid is drawn into the pump-barrel beneath the piston. Upon the reciprocal stroke of the piston the valve *p* will open, while the valve *r* will close, so that fluid will be forced through the opening in the piston-rod and the duct *i*. When the piston is making its downward stroke, the valve *q* will open, while the valve *o* will close, so that the air that is being forced upwardly through the piston-rod will be prevented from escaping into the pump-barrel, while at the same time fluid or air will be drawn into the pump-barrel from above, which will be forced through the piston-rod when it is again elevated, the valve *q* being closed, while the valve *o* is opened, when the piston-rod is moving upwardly.

While I have herein shown and particularly described the preferred form of my invention,

I do not wish to be limited to the precise construction illustrated; but,

Having thus described my invention, I claim as new and desire to secure by Letters Patent—

1. In a pump, the combination with the pump-barrel having its opposite ends provided with inlet-valves, of a piston arranged within the pump-barrel, a hollow piston-rod closed at its inner end and carrying the piston and having apertures in the portion of the piston-rod extending on opposite sides of the piston, and a loose strap arranged within the piston-rod and having portions adapted to serve as valves for closing the said piston-rod against the outflow of fluid, the said strap by its mounting being moved as the piston is reciprocated to bring its end portions alternately into valve-closing positions, substantially as described.

2. In a pump, the combination with a pump-barrel having its opposite ends provided with inlet-valves, of a piston arranged within the pump-barrel, a hollow piston-rod carrying said piston and having apertures on opposite sides of the piston, a strap arranged within the piston-rod and having portions adapted to serve as valves for closing said piston-rod against the outflow of fluid, pins connected with said strap and arranged to slide in said apertures, said pins being provided with heads adapted to prevent their being drawn through the wall of the piston-rod, and means for closing the inner end of the piston-rod, substantially as described.

3. In a pump, the combination with the pump-barrel, of inlet-valves arranged at the opposite ends thereof, a piston arranged within the barrel, a hollow piston-rod carrying said piston and having apertures on opposite sides thereof, means for closing the end of the piston, a strap arranged within the piston-rod and having portions adapted to provide inlet-valves for the said piston-openings, pins arranged to work in said openings and connected with the valve portions of said strap, the said pins having their outer ends enlarged, and a stop arranged above the uppermost of said valves, said stop comprising a collar having its upper surface provided with a recessed portion, substantially as described.

4. The combination with a pump-barrel, of a piston adapted for reciprocation therein, the hollow piston-rod carrying a piston, a valve interposed between the piston and one end of the pump-barrel, and a shield interposed between the said valve and the said end of the pump-barrel for intercepting foreign material that would otherwise flow into the hollow piston-rod, substantially as described.

In witness whereof I hereunto subscribe my name this 15th day of August, A. D. 1900.

ROBERT L. BENSON.
